UNITED STATES PATENT OFFICE.

FRED E. CARDY, OF CHICAGO, ILLINOIS.

ERASER.

Application filed August 5, 1921. Serial No. 489,983.

To all whom it may concern:

Be it known that I, FRED E. CARDY, a citizen of the United States, residing at Chicago, in the county of Cook and State of Illinois, have invented a certain new and useful Improvement in Erasers, of which the following is a full, clear, concise, and exact description, reference being had to the accompanying drawings, forming a part of this specification.

My invention relates to erasers designed primarily for use in removing chalk marks from blackboards or the like, and also to the method of making the same.

One of the objects of the invention is to provide a simple, practical and effective eraser.

Another object of the invention is to simplify the construction, and method of manufacture.

Another object of the invention is to secure durability and rigidity of construction.

Another object of the invention is to provide a stitched eraser having stitching only of such length as to permit it to be done in a practical manner and with stitching machines of the present day capacity.

Another object of the invention is to provide an advantageous method of making the erasers in quantity.

In the drawings Fig. 1 is a perspective view of an eraser embodying my present invention;

Fig. 2 is a longitudinal section of the same; Fig. 3 is a cross section taken on line 3—3 in Fig. 2;

Fig. 4 is a view similar to Fig. 1 of a modified form of device;

Fig. 5 is a similar view of a still further modification;

Fig. 6 is a longitudinal section of the device of Fig. 5;

Fig. 7 is a cross section taken on line 7—7 in Fig. 6; and

Fig. 8 is an end view of the device of Fig. 4.

Referring to the drawings, and particularly to Figs. 1 to 3, inclusive, I show an eraser having an outside strip, a part of which forms the back 1, said strip being preferably made of felt or other suitable material. This outside strip is also bent along the side edges of the back 1 to form projections 2—2 and thence downwardly to form outside side strips 3—3^a. Between the side strips 3—3^a there are intermediate strips 4—4 and

5—5, which with the side strips 3—3^a form the main body of the eraser. Between the back 1 and the strips 4—4 and 5—5 is a stiffening member 6 preferably made of hard felt or something of that sort. This stiffening member 6 also preferably extends into the side projections 2—2.

Stitching 7—7 extends through the side projections 2—2, passing also preferably through the stiffening member 6. Other stitching 8 secures the two strips 4—4 and the side strip 3 together; while still other stitching 9 secures the side strip 3^a and the strips 5—5 together. Thus the side 3 and the strips 4—4 form one part or half of the eraser body and the side 3^a and strips 5—5 form the other part or half of said body. Other stitching 10—10 extends through the back 1 and the stiffening member 6, and thence between the member 4—4 on the one hand, and members 5—5 on the other, and then engages the cross stitching 8—8 and 9—9, as shown in Fig. 3. The cross stitching 8 and 9 may be done by machine, and then the vertical stitching 10—10 may be done, also by machine, interlocking with the cross stitching 8 and 9. Thus the whole eraser is held together and although the body is composed of two parts this is not at all objectionable, as the two parts are held closely together.

In making the eraser a strip of felt long enough to make a plurality of erasers is laid out and the sides 3 and 3^a bent into position. The strips 4—4 and 5—5 are then put in position and the stitching 8—8 and 9—9 is done. Then the stiffening member 6 is put in position and the long back strip folded so as to bring the same and the strips 4—4 and 5—5 into proper relationship after which the stitching 10—10 is done. An elongated article adapted to make a plurality of erasers is thus formed and then this article is cut into lengths to form such erasers. This method is very simple and expeditious and at the same time allows a stitched eraser to be made without requiring stitching of excessive length to be done. For example, the stitching 8—8 and 9—9 is only about half the width of the eraser, as shown in Fig. 3, so as to permit a practical stitching operation to be performed. If such stitching had to be made through the entire width of the eraser it would be difficult or impossible.

In the modification shown in Figs. 4 and

8, the strips 4^a—4^a are sewed together by stitching 8^a, without being sewed to the strip 3; and the strips 5^a—5^a are sewed together by stitching 9^a, without being sewed either to the strip 3^a or the strips 4^a. This makes the cross-stitching through 4^a—4^a and 5^a—5^a, respectively, less than in the device of Figs. 1—3, because the outside strips 3 and 3^a are not included. The cross-stitching is then engaged by longitudinal lock-stitching 10—10, as in the other form, and stitching 7—7 is passed through projections 2.

In the modification shown in Figs. 5—7, inclusive, the outside member or strip 1 is omitted, the cross-stitching 8^a and 9^a being the same as in the device of Figs. 4 and 8, and lock stitching engaging the cross stitching 8^a and 9^a, and passing through the member 6, which in the absence of the member 1 becomes the top member. This makes a very simple, convenient and inexpensive form of eraser.

It will be understood that changes and modifications may be made without departing from the spirit of the invention.

What I claim is:

1. An eraser having its body formed of a plurality of connected parts, each of which is laminated, said parts being arranged side by side and in contact with one another, and stitching passing transversely through each of said parts without passing through any other part.

2. An eraser having its body formed of a plurality of longitudinally extending parts, each comprising a plurality of strips whereof the outer sides of the two outermost parts are formed by downward extensions of the eraser top, and stitching passing transversely through each of said parts without passing through any other part.

3. An eraser comprising a back formed of a piece of material which is bent along

its edges to form the outer sides of the eraser body and said body including strips arranged between said side strips, said intermediate strips being divided into two groups and the strips of each group being separately stitched to the adjacent side strip.

4. An eraser comprising integral back and side walls formed of a sheet of flexible material, and strips of flexible material between said walls, said strips being arranged parallel with said walls and divided into two groups, each of which is stitched to the adjacent wall, and other stitching passing through said back and engaging the first named stitching.

5. An eraser comprising integral back and side walls, formed of a sheet of flexible material, and strips of flexible material between said walls, said strips being arranged parallel with said walls and divided into two groups, each of which is stitched to the adjacent wall, and other stitching passing through said back and engaging the first named stitching, and a stiffening member interposed between the back and said intermediate strips and held in place by said last mentioned stitching.

6. An eraser comprising a back formed of a piece of material which is bent along its edges to form the outer sides of the eraser body and strips arranged between said side strips, said intermediate strips being divided into two groups and the strips of each group being separately stitched to the adjacent side strip, other stitching passing through the eraser back and engaging the aforesaid stitching, and a stiffening member interposed between the back and said intermediate strips and held in place by said last mentioned stitching.

In witness whereof, I hereunto subscribe my name this 29th day of July, A. D., 1921.

FRED E. CARDY.
